LETTER OPENER

Martin E. Trollen, St. Paul, Minn., assignor to
Brown & Bigelow, St. Paul, Minn., a corpora-
tion of Minnesota

Application December 11, 1939, Serial No. 308,627

4 Claims. (Cl. 30—342)

My invention relates to an improvement in letter openers or a similar device in which a blade must be attached to a handle.

Because of the popularity which articles formed partly of plastic have attained during recent years, it is desired to provide a letter opener or similar bladed instrument with a handle formed of plastic material. Such a handle, however, has certain undesirable features when used on a device of this sort. In the first place, unless the handle is formed of solid plastic, there is grave danger of splitting the handle as the instrument is used. In the second place, there is a tendency for the blade to move lengthwise within the handle, and such longitudinal movement of the blade must be resisted by small areas of the plastic. Thus a considerable longitudinal strain upon the blade will compress or deform the plastic and permit the blade to become loose upon the handle. Furthermore, with most types of handles, considerable assembly work must be done in assembling the blade upon the handle.

It is the purpose of my invention to provide a letter opener which combines a blade of metal or the like with a handle of plastic material or other similar material, and to accomplish this combination in a manner which will provide considerable strength at the point of connection. While the handle may be formed of comparatively thin plastic material, the blade is arranged in such a manner that the end of the blade is supported by reinforcing means within the handle which do not detract from the appearance of the instrument, but which provides the needed strength. Furthermore, my construction is such that the blade may be assembled in a minimum of time.

It is a feature of my invention to provide a hollow plastic handle having a closed end therewith provided with a slit through which the anchoring end of the blade may extend. This slit in the handle end provides a support which prevents rotation of the blade with respect to the handle, and as the flat portion of the blade end rests against the sides of the slots throughout the width of the blade, a firm bearing is provided to prevent rotation.

It is a feature of my invention to provide a reinforcing sleeve within the plastic barrel adjacent the end thereof of a diameter to fit closely about the anchoring end of the blade. This reinforcing sleeve transmits any strain from the blade to the sleeve, which in turn distributes the strain over a large area of plastic, thus pre-

venting the splitting of the plastic by pressure upon the blade.

It is a feature of my invention that the reinforcing sleeve is held in place against the closed end of the handle by means of locking shoulders on the anchoring end of the blade which engage over the end of the reinforcing sleeve. These shoulders prevent the blade from being pulled out of the slotted end of the handle and hold the reinforcing sleeve interposed between these locking shoulders and the closed handle end.

It is a feature of my invention that the anchoring end of the blade is slotted longitudinally to provide a bifurcated end structure to permit easy assembly of the blade and handle. After the reinforcing sleeve is in place within the handle, the anchoring end of the blade is compressed together, the bifurcated ends of this anchoring portion being drawn together under spring tension during the insertion of the blade into the handle. When the locking shoulders pass the inner end of the reinforcing sleeve, these shoulders snap out into engagement with the inner end of the reinforcing sleeve, holding the sleeve in place and simultaneously locking the blade from outward movement. The blade is so designed as to provide large shoulders between the anchoring end and the remainder of the blade, which shoulders may engage the reinforced end of the handle to prevent further inward movement of the blade. Thus when the blade has once been inserted in place, the locking shoulders and the shoulders between the anchoring ends of the blade and the remainder of the blade prevent longitudinal movement of the blade with respect to the handle in either direction.

It is a further feature of my invention to provide a thin metallic closure for the opposite end of the handle so that the inside of the handle may be sealed. This end closure may fit under spring tension within the open end of the handle.

These and other objects and novel features of my invention will be more clearly and fully set forth in the following specification and claims.

In the drawing forming a part of my specification:

Figure 1 is a side elevation view of the letter opener in assembled form.

Figure 2 is a side elevation view of the blade removed from the handle.

Figure 3 is a cross-sectional view through the blade, the position of the section being indicated by the line 3—3 of Figure 2.

Figure 4 is a longitudinal section through the

handle showing the construction thereof before the letter opener is assembled.

Figure 5 is an end view of the rear end of the handle before the knife is assembled.

Figure 6 is an end view of the forward end of the handle into which the knife blade extends before the blade is attached to the handle.

Figure 7 is an enlarged cross-sectional view through the assembled handle and blade showing the manner in which the locking sleeve holds the blade in position.

The letter opener A includes a handle 10 and a blade 11. The blade 11 may be of any desired conformation, but in the form shown is provided with a tapered end 12 evenly tapered on both sides of the longitudinal center of the blade. The preferred shape of the blade when used for a letter opener is shown in Figure 3 of the drawing, although the specific form of the outer end of the blade is not believed an important feature of the present construction.

The inner end of the blade is flattened as shown at 13 and attached to this flattened end 13 is a bifurcated end portion 14 of restricted width. The restriction in width of the bifurcated end 14 provides a pair of shoulders 15 which engage the end of the handle in a manner which will be later described. The anchoring end 14 of the blade 11 is provided with a longitudinal slot 16 providing two bifurcated ends 17. Each of the ends 17 are provided with an outwardly extending portion 19 forming a shoulder 20 between the projecting portions 19 and the remaining portion of the bifurcated ends 17.

The handle 10 is generally tubular in shape as best illustrated in Figure 4 of the drawing. This handle 10 is provided with an outwardly bulged or rounded closed end 21 which is provided with a transversely extending slot 22. This slot 22 extends entirely through the outwardly rounded closed end portion 21 and terminates in shoulders 23 at the end of the barrel 10.

A sleeve 24 of metal or similar material is positioned within the end of the handle 10 adjacent the closed end 21. This sleeve 24 fits closely against the shoulder 25 formed by the end 21 and is held from longitudinal movement in one direction by this shoulder 25. The sleeve 24 extends into the handle 10 a distance just sufficient to correspond in length with the bifurcated ends 17, between the shoulders 20 and the shoulders 15.

After the sleeves 24 have been inserted in the handle 10 and are held therein under friction, the bifurcated ends 17 of the blade 11 are squeezed together and the anchoring end 14 of the blade is inserted through the slot 22. As the ends 17 are compressed together, the projecting portions 19 engage the inner surface of the sleeve 24 and may be slidably moved through this sleeve. When the projections 19 reach the end of the sleeve 24, however, the bifurcated ends 17 spring apart and the shoulders 20 engage the inner extremity of the sleeve 24 preventing outward movement of the blade 11. Simultaneously, the shoulders 15 on the blade engage the shoulders 23 adjacent the slot 22 on the handle 10, so that the blade 11 is prevented from inward movement. The frictional engagement between the sleeve 24 and the handle 10 also reinforces the shoulders 23 adjacent the slot 24, as inward movement of the blade with respect to the handle would cause the shoulders 15 to bear not only against the shoulders 23 but also against the outer extremity of the sleeve 24.

In order to accomplish the desired result, it is necessary either to form the blade 11 out of sufficiently resilient material to cause the bifurcated ends 17 to spring apart after passing the end of the sleeve 24, or else to spread these arms after the blade is in place. In preferred form the blade is formed of material which will spring apart sufficiently to accomplish the desired result.

At the end of the handle 10 opposite the closed end 21 I enlarge the internal diameter of the tubular handle 10 as indicated at 26. This provides a shoulder 27 within the tubular member 10 at a point spaced from the outer handle end. A cap 29 which may be of metal or may be of plastic material is inserted in this enlarged diameter portion 26, the end of the cap engaging the shoulder 27, limiting inward movement of the cap. This cap 29 closes the outer end of the handle to prevent any material from entering the interior of the handle and also to improve the appearance of the letter opener.

In accordance with the patent statutes I have described the principles of construction of my letter opener; and while I have endeavored to set forth the best embodiment thereof, I desire to have it understood that this is only illustrative of a means of carrying out my invention and that obvious changes may be made within the scope of the following claims without departing from the spirit of my invention.

I claim:

1. A bladed instrument comprising a blade, a bifurcated resilient end thereon, shoulder means on said end, a handle comprising a tubular member, a sleeve therein of an inner diameter less than the distance between said shoulder means, a closed end on said tubular member through which said blade extends, said end extending through said sleeve and said shoulder means thereon engaging an end of said sleeve, the other end of said sleeve engaging said closed end.

2. A bladed instrument comprising a blade, a bifurcated end thereon, a shoulder means between said end and the remainder of the blade, a tubular handle having a closed end thereon, a slot in said closed end through which said blade end extends, an inwardly projecting sleeve in said handle of an inner diameter to encircle said bifurcated end, shoulder means on said bifurcated end engagable with an end of said sleeve, the other end of said sleeve engaging said closed end.

3. A bladed instrument comprising a tubular handle, a closed end thereupon, a slot in said end, a sleeve in said handle adjacent said end, a blade, a bifurcated end thereon extending through said slot, a shoulder between said blade and said bifurcated end engageable with said handle, and shoulder means on said bifurcated end engagable with said sleeve, said sleeve being held between said shoulder means and said closed handle end.

4. A bladed instrument comprising a blade, a flat bifurcated shank thereupon, shoulder means on said shank, a hollow handle having a closed end having a slot therein to receive said shank, shoulder sleeve means in said handle cooperable with said shoulder means on said end to prevent movement of said blade in said slot in one direction, and a second shoulder means on said blade cooperable with said handle adjacent said slot to prevent movement of said blade in said slot in the opposite direction.

MARTIN E. TROLLEN.
